UNITED STATES PATENT OFFICE.

JOHN O. REMINGTON, OF HINGHAM, MASSACHUSETTS.

DESIGN FOR A SHADE-TASSEL.

SPECIFICATION forming part of Design No. 23,259, dated May 15, 1894.

Application filed March 17, 1894. Serial No. 504,097. Term of patent 3½ years.

To all whom it may concern:

Be it known that I, JOHN O. REMINGTON, a citizen of the United States, residing at Hingham, Plymouth county, State of Massachusetts, have invented and produced a new and original Design for Shade-Tassels, of which the following is a specification, reference being had to the accompanying drawing, which represents a fac-simile of the same.

10 The leading features of my design consist in a tassel having a head which is provided with two loop ruffs.

15 The shade tassel comprising my design consists of a skirt 2 and a head 3, the body of this part of the tassel is covered with piping 4, wound about it. The general effect being that of a coil or spiral. Midway of the head and at the dividing line between the skirt and the head are secured two ruffs 5, 6 upper

and lower respectively. These are termed 20 loop ruffs since the material composing them is arranged in a series of loops in lieu of being cut. The effect of the loops when grouped or massed to produce a ruff is to present a wavy appearance. The lower ruff is to be of 25 greater thickness than the upper consisting of two or more rows of loops as may be desired.

What I claim is—

20 The design for a shade tassel, substantially 30 as specified and described.

In testimony whereof I affix my signature in the presence of two witnesses.

JOHN O. REMINGTON.
